INCINERATION OF SMOKE AND INDUSTRIAL FUMES

Joseph Jares, Brooklyn, N. Y.

Application December 12, 1936, Serial No. 115,493

7 Claims. (Cl. 183—6)

This invention relates to the destruction and elimination of smoke, objectionable fumes and fly ash from chimneys.

While especially adapted for the elimination of odorous gases ordinarily discharged from chimneys of garbage and refuse incinerators, the invention is adapted as well for the disposal of the objectionable, combustible fumes from industrial operations involving treatment of oil, paint, varnish, lacquer vapors, waste gases from chemical plants and the like.

Particular objects of the invention are to provide an incinerator of the nature and for the purposes mentioned, which will be effective to completely consume and destroy smoke, fumes, fly ash and the like, which may be readily applied to existing equipment, which will have low fuel and power requirements and which will be generally desirable in other ways.

20 The foregoing and other objects are attained by the novel features of construction, combinations and relations of parts hereinafter described, illustrated in the accompanying drawings and broadly covered in the claims.

25 The drawings illustrate certain practical embodiments of the invention, but structure may be modified and changed as required for different installations, all within the true intent and broad scope of the invention.

30 Figure 1 is a broken vertical sectional view showing an embodiment of the invention installed in an incinerator chimney.

Figure 2 is a broken sectional view showing parts as they appear on substantially the plane of line 2—2 of Figure 1.

Figure 3 is an enlarged broken sectional detail of one of the burner tubes as on substantially the plane of line 3—3 of Figure 1.

Figure 4 is a fragmentary sectional enlargement illustrating a suitable form of draft-proof nozzle for the pilot lights and burner ports.

Figure 5 is a broken vertical sectional view illustrating modifications partially for a larger form of combustion unit.

15 Figure 6 is a broken vertical sectional view illustrating application of the invention to an industrial drying oven.

Figures 7 and 8 are longitudinal sectional views of combustion units designed for industrial uses such as illustrated in Figure 6.

At present, the usual means for prevention of fly ash from garbage and refuse incinerators are simply so-called "cinder catchers" in the form of metal screens on the tops of incinerator chimneys. Being entirely exposed to the weather,

these screens soon disintegrate and have to be frequently replaced at considerable cost and hazard to workmen. These cinder catchers only hold back the coarse pieces of fly ash and have no destructive effect on the smoke resulting from partial combustion of garbage and refuse which constitutes both a nuisance and a serious menace to public health.

The present invention overcomes objections such as those mentioned and is based upon certain original discoveries. These are:

First, light smoke; that is, colloidal particles and odorous flue gases can be quickly and completely destroyed by ignition with gas flames and then passage through red hot metal screens or between red hot thin metal strips or wires.

Second, heavy smoke, involving coagulated particles and carbonaceous fly ash particles can be completely consumed by gas flames in an oxidizing atmosphere when in a turbulent condition.

Third, coarse particles of fly ash can be completely burned up by radiant heat when in a state of rest.

Fourth, mineral ashes resulting from combustion of carbonaceous fly ash can be precipitated back into the incinerator by specially arranged metal screens.

The combustion unit shown in Figures 1 and 2 is designed for the destruction of all smoke and fly ash from a garbage and refuse incinerator and is in a form such that it may be mounted in the incinerator chimney without interfering with the natural draft and at a point where it will offer no obstruction to the discharging of materials into the incinerating furnace.

The unit illustrated is composed of oppositely disposed gas burners 10 within the incinerator flue 11, discharging upwardly beneath inclined screens 12 and having below them, the upwardly inclined wire guards 13. Air for complete combustion is supplied beneath the guards by perforated fresh air pipes 14, connected at the outside with a blower or other suitable air supply source.

Each gas burner is provided with one or more rows of alternately large and small flame ports 15, 16, Figure 3, discharging on an upward inclination such as shown in Figure 1 and arranged so that the flame from the smaller ports will practically fill in the spaces between the flames issuing from the larger and longer ports, thus to substantially cover with flame, the entire under surfaces of the upwardly convergent screens 12.

The screens 12 are preferably made of heat resisting wire and have frames of similar heat

55

resisting material. While the inclination may vary, it has been found practical to incline them on an angle between 45° and 60° to the horizontal.

The burner tubes are shown as having V notches 18 in the top of the same providing seats for the screen frames 19 and at the top these frames are shown entered in rectangular notches 20 at the under side of a T bar 21, extending across the chimney. With this construction the screens are definitely held in place, but may, if desired, be removed by sliding them out through a doorway 22 in the side of the flue.

Extending downwardly between the two screens are shown a pair of closely spaced vertical screens 23, forming with the latter in effect, triangular combustion zones into which the burners discharge.

The guard screens 13 are shown as made up of spaced vertical wires and they are indicated as extending from supporting brackets 24 on the sides of the chimney upwardly, above the air pipes 14 to the foot of the vertical screens 23. In this particular disclosure, the vertical screens are shown as supported between the cross bar 21 at the top and a lower cross bar 25, and the latter is illustrated as carrying hook-like brackets 26 over which the upper ends of the wire guards are engaged. These guards are shown as pitched at a steeper angle than the screens 12 but this, while usually desirable, is not essential.

Air from a blower or other source is supplied through piping 27 to the burners 10 and perforated air supply pipes 14 and gas through external piping 28 to the burners and to a suitable pilot 29, Figure 2. These pilots may have nozzles of the draft-proof type such as indicated at 29 in Figure 4. The perforated pipes 14 projecting horizontally across the path of smoke and flue gases below the wire racks furnish air for combustion of smoke and carbonaceous fly ash.

The alternately large and small burner ports set at different elevations accomplish two desirable results. First, they insure positive flame travel from port to port, the entire length of a row of ports from the pilot flame applied to the first port so that all flames stay lit when exposed to the draft of the chimney; and secondly, the higher elevation of the larger ports causes the flames from these to extend full width across the inclined screens with minimum gas consumption, the flames from the smaller ports covering and filling in the triangular screen areas below the points of merger of the larger flames. This alternative arrangement of larger and smaller, higher and lower flame ports also permits wider port spacing and produces more nearly uniform heat distribution over the entire screen area with minimum gas consumption.

The flame ports are shown as angled slightly below a plane parallel with the overlying screen to prevent direct impingement of individual gas flames against the inclined screen surface and so to complete combustion of gas below the screen level. This method of firing allows for free passage of the flue gases, effects longer screen life and affords substantially uniform heat distribution.

The screens provide a maximum heating surface to complete combustion of light smoke and malodorants with minimum restriction of chimney area. As the gas flames are uniformly distributed below the screens, all rising smoke is ignited when coming in contact with the gas flames and combustion of same is completed by passage through the red hot screen surfaces.

The vertical screens 23 form with the inclined screens 12, triangular zones of turbulence into which the heavier coagulated smoke particles and small carbonaceous fly ash are deflected by the gas flames. The larger of these particles are thus made to impinge against the vertical screen surfaces where they are held back until consumed.

Mineral ash which clings to the vertical screen surfaces 23 becomes incandescent, forming radiating refractory which further assists in the combustion process. At the end of each incinerating period most of this mineral ash will drop, on cooling and if required, any remainder may be easily brushed off at periodic inspection and cleaning 15 times.

The wire guards 13 hold back larger pieces of fly ash, such as burning papers, preventing it reaching the combustion zone where it might temporarily interfere with proper operation of 20 the gas burners. Any such large pieces of fly ash are deflected and carried by the draft upwardly between the inclined guards where exposed to radiant heat from above and supplied with fresh air from below, they are quickly consumed.

In the chimney-fed type incinerators, the complete combustion unit may preferably be located directly above the topmost hopper door. In basement-fed type incinerators, the unit may be 30 located a short distance above the flue pipe connecting the incinerator with the chimney. For use with industrial incinerators, the combustion unit may be modified for installation in horizontal position and may be incorporated as an integral part of the incinerator construction.

In the modification shown in Figure 5, the two burner tubes 10a are located at intermediate points instead of at the sides of the chimney and the screens 12a are disposed in W formation with 40 the lower edges seating in V-shaped notches 18a in the tops of the burner tubes. The vertical screens 23a are disposed at the sides of the outer screens as well as dependent from in between the inner pair of screens, providing in this instance, 45 four triangular combustion spaces for the flames projecting from opposite sides of the burner tubes.

In Figure 6 the invention is shown applied to the destruction of combustible fumes from industrial operations. Usually industrial fumes are free from suspended matter and sufficiently diluted with air so the fly ash retaining guards and fresh air supply pipes are not required.

In the illustration, Figure 6, a drying oven of the 55 conveyer type is indicated at 30, having an exhaust duct 31 in the upper portion of the oven chamber and an inlet duct 32 in the lower portion of the chamber. A blower is indicated at 33 for withdrawing hot fumes from the exhaust duct and for 60 returning these through a pressure conduit 34 to the inlet duct 32. The combustion unit is indicated generally at 35, interposed in the outlet conduit 36 extending from the exhaust duct 31 to the intake side of the blower.

It has been found by experiment that combustible solvents on the coated sheets or articles passing through the furnace are completely volatilized by action of heat within a relatively short range of travel through the first portion of the 70 oven chamber. Accordingly in the present invention, this localized portion of the exhaust duct, represented at 31a, is cut off from the main length of the exhaust duct as indicated at 37, and vapors from this first section are conducted directly 75

through conduit 36 into the combustion unit 35 where they are consumed and then passed on as inert hot gas suitable for return by the blower to the oven for drying and heating purposes. The remaining portion of the exhaust duct is separately connected by an off-take 38 connected into the exhaust conduit 36 ahead of the fume incinerating air heating unit 35. With this construction the first, separate section of the fume collecting duct picks up practically all the combustible fumes and considerable fuel savings are effected since no excessively large volumes of highly diluted vapors are needlessly heated.

Figure 7 shows how the unit may be modified for such an industrial use by constructing the burner as a complete cylindrical element 10b set in the end of the cylindrical section of exhaust piping 36 and the incinerating screen 12b be constructed as a frustoconical member supported at the base end 20 on the burner ring and at the tip end on a reversely faced cone 40, providing in this instance, the turbulent combustion space 41 of conical ring form instead of the triangular shape first described.

Where electric heating is preferred, the gas heated incinerating cone may be replaced by an electric heating element or elements such as indicated at 42 in Figure 8, wound spirally in a conical screen form providing sufficient area of contact for ignition of all vapors. In such construction the inflammable vapors are ignited by contact with inside segments of the spirally wound wires and combustion is completed on contact with the outside segments of these hot wires. The burner ring and supporting cone also are replaced in this construction by a suitable supporting ring 43 of insulating material and by an insulating conical support 44.

To save fuel or energy required for operation, the combustion unit should be located as near as possible to the source of fumes so that the initial heat content will be fully utilized. Thus, for example, when used for the disposal of fumes from oil, varnish cooking kettles and the like, the unit preferably should be inserted in the fume exhaust duct close to the kettle or the last of a series of kettles.

In all forms, the invention may be constructed as a complete combustion unit, ready for installation in or as in Figures 6, 7 and 8, to form part of an exhaust chimney or duct.

I claim:

1. A heating unit for incineration of smoke and industrial fumes comprising a heated fume consuming screen convergent in the direction of flow, means for mounting said heated convergent screen in flow intercepting relation in a chimney or like smoke and fume conducting passage and gas burners discharging at the inner surface and

arranged to spread flame over substantially the entire inner surface of said convergent screen and having relatively large and small flame ports in alternating order with the smaller flame ports of lesser elevation and discharging in the spaces between the larger flame ports. 5

2. A heating unit for incineration of smoke and industrial fumes comprising a heated fume consuming screen convergent in the direction of flow, means for mounting said heated convergent screen in flow intercepting relation in a chimney or like smoke and fume conducting passage, means for positively furnishing a supply of fresh air under pressure within the convergent screen and a guard grid interposed between said fresh air supply means and the interior of said convergent screen. 10 15

3. A heating unit for incineration of smoke and industrial fumes comprising a heated fume consuming screen convergent in the direction of flow, means for mounting said heated convergent screen in flow intercepting relation in a chimney or like smoke and fume conducting passage and including a burner body, said burner body having means for supporting said convergent screen 20 directly thereon and said burner body having flame ports directed over the inner surface of said convergent screen. 25

4. A heating unit for incineration of smoke and industrial fumes comprising convergently arranged screens, burners discharging flame over the inner inclined faces of said convergently arranged screens and inclined grids forming guards over said burners. 30

5. A heating unit for incineration of smoke and industrial fumes comprising convergently arranged screens, burners discharging flame over the inner inclined faces of said convergently arranged screens, inclined grids forming guards over said burners and a perforated air supply 40 pipe or pipes within said inclined guard grids. 40

6. A smoke and fume incinerator for an incinerator chimney comprising upwardly convergent screens, a substantially vertical screen between said convergent screens and burners discharging into the substantially triangular spaces 45 between said upwardly convergent and substantially vertical screens.

7. In a heating unit for incineration of smoke and industrial fumes, a conduit for such smoke 50 and fumes, a screen in said conduit and inclined in the direction of flow therethrough and a gas burner having ports discharging across the inner face of said inclined screen, said ports being of different elevations and sizes to spread the 55 flame substantially uniformly across said inner face of the inclined screen.

JOSEPH JAMES.
